The ornamental design for an adjustable hanging rod, as shown and described.

DESCRIPTION

FIG. 1 is a front perspective view of an adjustable hanging rod, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of its folded state; and,

FIG. 10 is an enlarged detail view of area 10 in FIG. 1.

The broken lines in the drawings illustrate the portions of the adjustable hanging rod, which form no part of the claimed design.

The dash-dot-dash broken lines encircling the enlarged views are for annotative purposes only and form no part of the claim thereof.
